UNITED STATES PATENT OFFICE.

CHARLES E. FARRINGTON, OF PHOENIXVILLE, PENNSYLVANIA.

BARREL AGITATOR.

Application filed May 22, 1924. Serial No. 715,095.

To all whom it may concern:

Be it known that I, CHARLES E. FARRINGTON, citizen of the United States, residing at Phoenixville, in the county of Chester and State of Pennsylvania, have invented new and useful Improvements in Barrel Agitators, of which the following is a specification.

This invention relates to agitators for stirring the contents of a barrel or drum wherein such materials as paints and other suspensions or mixtures of various materials may be confined. In my Letters Patent No. 1,336,830 dated April 13, 1920, I have disclosed an agitator consisting of a blade which is rotatable about an axis approximately coincident with the barrel or drum, and which is provided with a weight pivoted upon a radial portion of the blade to swing outwardly and operate in the angle formed by the bottom and side wall of the container.

I have found in some cases, that even with the device described, it is difficult to loosen and mix with the remainder of the contents of the tank, the solid or more viscous sediment or material which forms and is apt to cake on the bottom of the tank and in the angle referred to, and further that, when the bottom of the tank becomes malformed because of rough usage and depressions are formed therein, the difficulty increases. The present invention has for its object to provide means for more effectively removing the sediment or deposit at the bottom and in the angle of the tank.

On the drawing,—

Figure 1 represents in vertical section a barrel provided with an agitating device embodying my invention.

Figure 2 represents a horizontal section through the same on line 2—2 of Figure 1.

Figure 3 represents in section the bottom portion of a wooden barrel, and shows the flexible scraper in operation.

Figure 4 shows how the scraper will operate if the end of the barrel or drum be deformed.

The container 10 may be barrel-shaped or it may be cylindrical, and has, of course, a side wall 11, and the two ends 12 and 13, with the reentrant angle 14 formed by the bottom 12 and side wall 11. Any suitable stirrer may be employed having a radial arm *a*, movable about an axis substantially

coincident with the axis of the container in approximately horizontal planes parallel with and adjacent to the bottom 12. Preferably the stirrer consists of a single thin rigid blade 140 comprising in addition to the arm *a*, which is edgewise vertically, and the upwardly extended twisted portion *b* having its extremity *c* engaged with a member 15 by which the blade may be rotated by the use of a suitable detachable handle. At its inner extremity, the portion or arm *a* is pivoted on a stud secured in the center of the bottom 12. The outer end of the arm *a* connects with the upwardly extending portion *b* by a bend or twist *d*. These features, which are all disclosed in my said Letters Patent, may be varied, however, as occasion demands.

The present improvement resides in a flexible scraper which preferably takes the form of a relatively heavy metal chain formed of a series of links, as indicated at 17, and having one extremity secured at or near the inner end of the agitator arm *a*, and its other extremity secured at or near the outer end of the arm,—in the present instance in the bend *d*. Any suitable means may be employed for securing the end links of the chain, such as hooks 18, engaging eyes 19 attached to the arm *a*. The chain is considerably longer than the distance between the eyes 19, so that normally the intermediate part of the chain rests loosely upon the bottom of the container, as shown in Figure 1. By rotating the agitator slowly about its axis, the depending intermediate portion of the flexible scraper scrapes along the bottom 12 and extends into depressions in the bottom, as shown in Figure 4, so as thoroughly to loosen and remove any sediment or deposit on the bottom; and then by rotating or revolving the agitator at sufficient speed to subject the flexible scraper or chain to centrifugal action, the latter will be caused to scrape along the surfaces at the angle formed by the bottom and the side wall of the container. While a relatively heavy chain is the preferred form of the invention, any equivalent, which when suspended at its ends will form a catenary curve, may be used provided it is of sufficient weight and flexibility to function.

What I claim is:

1. An agitator for a barrel or like container, comprising an arm revoluble about

- the axis of the container and extending outwardly from said axis toward the side wall of said container and thence upwardly, and a flexible scraper having its ends attached to the arm and depending therefrom, so as to be dragged thereby over the bottom of the container when the arm is revolved, such scraper being of such length that its intermediate portion may operate in the angle formed by the bottom and side wall of the container.
2. An agitator for a barrel or like container, comprising an arm revoluble about the axis of the container and extending outwardly from said axis toward the side wall of said container, and a chain having its ends attached to said arm adjacent the end portions thereof, and having a loose depending intermediate portion to operate on the bottom of the container and in the angle

formed by said bottom and the side wall of said container.

3. An agitator for a barrel or like container, comprising an arm revoluble about the axis of the container and extending outwardly from said axis toward the side wall of said container, and thence upwardly, and a flexible scraper having one end attached to the inner end of the arm and its other end to the upwardly extending outer portion of said arm, and depending therefrom, so as to be dragged over the bottom of the container when the arm is revolved, said scraper being of such length that its intermediate portion may operate in the angle formed by the bottom and the side wall of the container.

In testimony whereof I have affixed my signature.

CHARLES E. FARRINGTON.
